NAIL DRIVING ATTACHMENT FOR
PNEUMATIC HAMMERS

Claude D. Raybourn, Denver, Colo.

Application March 20, 1945, Serial No. 583,821

4 Claims. (Cl. 1—46.1)

1

This invention relates to a nail feeding and driving attachment for pneumatic and electric hammers and riveting guns and the like, and has for its principal object the provision of a light, simple, compact device which can be quickly and easily slipped into place on a portable power hammer; which will hold a supply of nails; which will feed the nails one at a time to a driving mechanism; and which will drive the individual nails fully into the work.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved nailing attachment in place on a typical riveting gun. The attachment is partially broken away to illustrate its interior construction, and the nail is shown partially driven.

Fig. 2 is a similar view illustrating a second nail being fed into position for driving.

Fig. 3 is a vertical section, taken on the line 3—3, Fig. 2.

Fig. 4 is a similar section, taken on the line 4—4, Fig. 1.

Fig. 5 is a reduced scale side view of the improved attachment.

Fig. 6 is a section showing the path of the nails from the magazine to a position in the driver channel.

The nose of a typical pneumatic riveting gun or hammer is illustrated in the drawing at 10 with its snap attachment spring at 11 and driving piston at 12; typical nails are illustrated at 18, their heads at 17, and the work into which the nails are to be driven at 22. The improved attachment comprises a frame member 13 from which a hand grip 14 projects rearwardly and downwardly, and a nail feeding chamber 15 projects upwardly.

The width of the nail feeding chamber is just sufficient to allow the shanks of the nails to pass downwardly therethrough in a single vertical row. The rear portion of the chamber 15 is formed with nail head channels 16 at each side to accommodate the width of the heads of the nails, and the chamber is inclined rearwardly so as to allow the nail heads 17 to overlap in stag-

2

gered relation, as shown in Fig. 1. The lower portions of the nail head channels 16 terminate in forwardly extending horizontal channels 19 which allow the nail heads to be moved forwardly to in downwardly opening outlet channels 20. The bottoms of the channels 19 extend inward toward each other to form parallel ledges 35 which are spaced apart just sufficiently to allow the shanks of the nails to drop downwardly therebetween. The space between the ledges, however, is not sufficient to allow the heads to drop therebetween so that the lowermost nail is supported by its head and the superimposed nails are supported thereon, as shown in Fig. 2. The ledges terminate at the outlet channels 20 so that if the lowermost nail is forced forward in the channels 19 until its head reaches the outlet channels 20, then the entire nail will drop from the chamber 15.

20 In use, the nails 18 are piled in the chamber 15 and as each nail is used the next successive nail moves downwardly to the horizontal channels 19, thence forwardly therein until the outlet channels 20 are reached, which allow it to fall from the chamber 15.

25 A driving bore 21 extends horizontally through the frame 13 immediately below the chamber 15. A hammer rod 22 is axially mounted in the bore 21 and projects rearwardly from the frame 13. The forward extremity of the rod 22 is enlarged to provide a hammer head 33. A snap spring spool 34 is formed on the rod 22 near its rear extremity which enters, and is held in place by, the snap spring 11 of the gun 10 similarly to 30 the usual riveting or caulking snaps with which such tools are provided. The rearward extremity of the rod extends into the gun 10 to a point where it will be struck by the driving piston 12.

35 The rod 22 passes through a slidable injector block 23 within the frame 13. The injector block is constantly urged forwardly against a stop shoulder 24 by means of a compression spring 25. The block 23 rides in an enlargement of the bore 21 at the rear portion of the latter and is provided with a head socket 26 for receiving the hammer head 33 and with a head-engaging tooth 27 which extends upwardly into the horizontal channel 19 between the two ledges 35.

40 A nail-guiding dog 28 is mounted above and below the forward extremity of the bore 21. The guiding dogs 28 are preferably triangular in shape and hinged on hinge pins 29 adjacent their rearward apexes. The dogs 28 are urged together 45 in the bore at their forward extremities by

means of compression springs 30. The contacting edges of the dogs are concave, as shown in Fig. 3, so as to force the nails to an axial position in the bore 21.

The frame 13, grip 14, and chamber 15 may be formed from two similar, opposite-hand halves held together by means of suitable rivets or clamp screws 31. These elements, however, could be formed from a single cast or molded block of material such as aluminum or plastic, if desired.

In use, the chamber 15 is filled with nails and the rearward extremity of the rod 22 is inserted in the hammer 10. The head of the frame 13 is placed against the surface of the work 32 at the point where the nail is to be driven. The riveting gun 10 is then pulled rearwardly from the frame 13 (see Fig. 2). This causes the hammer head 33 to enter the head socket 26 in the injector block 23 and pull the block 23 rearwardly against the action of the spring 25.

When the forward face of the injector block 23 passes the head of the lowermost nail, the gun 10 is pushed forwardly. This allows the spring 25 to push block 23 forwardly with the tooth 27 in contact with the head of the lowermost nail. This pushes the latter nail forwardly, its head being supported by the ledges 35 until the latter terminate at the discharge passage 20 allowing the head of the foremost nail to fall into the bore 21. Further forward movement of the gun pushes the hammer head 33 against the nail and the latter pushes the nail between the dogs 28 and against the work.

The riveting gun 10 is now operated to reciprocate its drive piston 12 against the extremity of the rod 22, which in turn forces the head 33 to drive the nail into the work, as shown in Fig. 1. The driving is continued until the head 33 passes between the dogs 28 and against the work 32, thus completely driving the nail into the work. The next nail is then fed into the bore 21 by pulling the riveting gun 10 rearwardly from the frame 13 as before.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A nail driving attachment for power hammers comprising: a frame member; a horizontal bore in said frame member; a driving rod extending axially of said bore and projecting from the rear of said frame member; a driving head on said rod within said frame member; means for attaching the rearward extremity of said rod to a typical power hammer; a nail feeding chamber above said bore, having a width slightly in excess of a single nail for holding a vertical pile of nails above said bore; head channels in each side of said chamber for receiving the heads of said nails; horizontal head channels in the sides of said chamber at the lower extremity of said head channels for allowing the heads of the nails to move forwardly in said chamber; and a vertical feed channel at the forward extremities of said head channels, allowing the heads of said nails to drop into said bore forwardly of said driving head.

2. A nail driving attachment for power hammers comprising: a frame member; a horizontal bore in said frame member; a driving rod ex-

tending axially of said bore and projecting from the rear of said frame member; a driving head on said rod within said frame member; means for attaching the rearward extremity of said rod to a typical power hammer; a nail feeding chamber above said bore, having a width slightly in excess of a single nail for holding a vertical pile of nails above said bore; head channels in each side of said chamber for receiving the heads of said nails; horizontal head channels in the sides of said chamber at the lower extremity of said head channels for allowing the heads of the nails to move forwardly in said chamber; a vertical feed channel at the forward extremities of said head channels, allowing the heads of said nails to drop into said bore forwardly of said driving head; and means for moving said heads forwardly in said horizontal head channels.

3. A nail driving attachment for power hammers comprising: a frame member; a horizontal bore in said frame member; a driving rod extending axially of said bore and projecting from the rear of said frame member; a driving head on said rod within said frame member; means for attaching the rearward extremity of said rod to a typical power hammer; a nail feeding chamber above said bore, having a width slightly in excess of a single nail for holding a vertical pile of nails above said bore; head channels in each side of said chamber for receiving the heads of said nails; horizontal head channels in the sides of said chamber at the lower extremity of said head channels for allowing the heads of the nails to move forwardly in said chamber; a vertical feed channel at the forward extremities of said head channels, allowing the heads of said nails to drop into said bore forwardly of said driving head; an injecting block mounted on said rod adjacent said horizontal head channels; means on said block for engaging the head of a nail positioned in said latter channels; means for reciprocating said block to force the nails forwardly in said horizontal head channel; and a vertical feed channel at the forward extremities of said horizontal channels, allowing the heads of said nails to drop to said bore forwardly of said driving head.

4. A nail driving attachment for power hammers comprising: a frame member; a horizontal bore in said frame member; a driving rod extending axially of said bore and projecting from the rear of said frame member; a driving head on said rod within said frame member; means for attaching the rearward extremity of said rod to a typical power hammer; a nail feeding chamber above said bore, having a width slightly in excess of a single nail for holding a vertical pile of nails above said bore; head channels in each side of said chamber for receiving the heads of said nails; horizontal head channels in the sides of said chamber at the lower extremity of said head channels for allowing the heads of the nails to move forwardly in said chamber; a vertical feed channel at the forward extremities of said head channels, allowing the heads of said nails to drop into said bore forwardly of said driving head; an injecting block mounted on said rod adjacent said horizontal head channels; means on said block for engaging the head of a nail positioned in said latter channels; a vertical feed channel at the forward extremities of said horizontal channels, allowing the heads of said nails to drop to said bore forwardly of said driving head; a spring constantly urging said injecting block forwardly to force

nails forwardly in said horizontal channels; and means on said rod for engaging said block to move it rearwardly.
